7 Claims. (Cl. 22—3)

This invention relates to machines for casting stereotype plates and has for its object to provide a fully automatic machine which will continuously cast plates in any desired number from a single matrix, move the freshly cast plates to an inspection station and thence to and through the plate trimming machine and the cooling machine, and thence to the discharge conveyor, all without handling by the operator. Stereotype plate casting machines are now manufactured wherein the plates are cast, trimmed and cooled. Such machines, however, require hand manipulation to effect the opening and closing of the casting box and the delivery of the plate into the trimming section.

The plate casting machines now on the market can produce at a maximum approximately three plates per minute, whereas the machine embodying the invention of the present application can produce between four and five plates per minute. Moreover, in the machine of the present application the plates are constantly subject to inspection, as the machine is entirely automatic and the trimming of the previously cast plate and the casting of the succeeding plate are going on while the intermediate plate is inspected. Also, discarding the plate if found imperfect does not in any way interfere with the operation of the machine, but merely restricts the output of the machine for that particular minute to three or four plates instead of four or five. No operator is required for the machine save the inspection operator, for at the inspection stand a control button is provided by which the machine may be stopped in an emergency and restarted should it be necessary for any reason to interrupt the continuous automatic operation of the various parts of the machine.

In accordance with the present invention the casting box is arranged with the axis of the core parallel with the axis of the trimming arch and the molten metal is forced under pressure into the lower open end of the mold and maintained under pressure during the cooling period. At the conclusion of the cooling period the casting box is opened, the core is revolved around its axis through a movement of 180° and upon again closing the casting box the plate is elevated by rollers carried by the casting box to thereby bring the edges of the plate in alignment with the rollers which support the plate as it moves to the inspection station and thence to the plate trimming and cooling sections. After the casting box is thus closed the metal for a second plate is discharged into the casting box. While this is taking place the operator at the inspection stand inspects the plate and if defective can, by a plate discharge device, discharge the defective plate onto a conveyor leading to the furnace so that the defective plate is immediately returned to the furnace where the metal is reused. If the plate is found satisfactory it is automatically shifted into the trimming section of the machine.

In the accompanying drawings we have illustrated the entire casting machine and have shown in detail the new

2

casting box and inspection apparatus and in the said drawings

Fig. 1 is a side elevation of the entire machine;

5 Fig. 2 is a vertical section on a somewhat enlarged scale of the casting box and a portion of the machine adjacent the casting box showing the mechanism for opening and closing the casting box;

10 Fig. 3 is a similar sectional view of the portion of the machine including the inspection station and certain adjacent parts and the mechanism for operating certain parts as hereinafter described;

15 Fig. 4 is an enlarged partial sectional view on line 4—4 of Fig. 2;

Fig. 5 is a similar partial sectional view on line 5—5 of Fig. 2; and

Fig. 6 is a detail view showing the mechanism for operating the inspection stand to discard an imperfect plate.

20 Referring to the drawings, particularly to Fig. 1, 1 indicates the plate casting section, 2 an intermediate station between the casting section and the inspection stand 3, 4 the trimming section and 5 the cooling section. The trimming and cooling sections are of the same construction as embodied in plate casting machines 25 now on the market, and this portion of the machine will not be further described.

25 The plate casting and inspection portions of the machine, shown in detail in Figs. 2 to 6 comprises a cylindrical core 6 mounted for rotation and so positioned that 30 the axis of the cylindrical core of the core box is parallel with the axis of the trimming arch but lower than the axis of the trimming arch so that when the plate is lifted from the core its edges will be in line with the rollers upon which the plate is supported in its passage 35 through the inspection station and into the trimming section. The cylinder 6 is a hollow drum the interior of which is connected through hollow bearings with the cooling water circulating system which will not be described in detail. The casting box consists of a semi-cylindrical hollow shell 8 whose concave face forms the 40 seat for the matrix and is provided with matrix holding devices of usual design, not shown. The casting box is formed with the usual vacuum chamber 9 and cooling water compartments. The casting box is positioned 45 below the cylindrical core and is mounted for movement toward and away from the core. After the plate is cast the casting box is lowered to open the mold, by a mechanism to be later described. The core is then automatically rotated alternately in opposite directions.

50 50 through 180° by an hydraulic motor whose operation is controlled by an automatic timing system, not shown. The half rotation is followed by a period of rest during which the casting box is elevated, thereby lifting the cast plate from the core and closing the mold to receive 55 the metal for a second plate. The molten metal from the furnace is discharged into the mold through nozzles 20 in the cover plate of the discharge manifold 21, shown in Fig. 2.

60 As here shown the molten metal manifold is semi-circular in shape and supported adjacent the lower end of the cylindrical core. The portion of the manifold contacting the adjacent core consists of a plate 22 formed with an axially projecting rib 23 through which rib the discharge nozzles 20 are formed by holes drilled through 65 the rib and communicating with the interior of the manifold. These nozzles are closely spaced throughout the length of the rib so that the molten metal will be discharged into the mold at a rate to rapidly fill the mold before the metal begins to solidify. The manifold is supported in fixed position and the upper edge of the rib 23 is fitted accurately against the adjacent perimeter of the core. The lower face of the rib 23 is likewise accurately

finished to fit against a complementary surface formed on the adjacent edge of the casting box so that when the casting box is closed and held in closed position under pressure there will be a metal tight joint on both faces of the rib, thereby preventing any leakage of the molten metal.¹

The casting box is connected through a fixed pipe 24 with the molten metal pump, not shown, but it will be understood that the pump is operated in timed sequence with the closing of the mold so as to discharge molten metal through the pipe 24 into the manifold 21 under pressure and maintain that pressure on the metal for a sufficient period for the metal in the casting cavity to solidify. At the end of this time interval the movement of the piston of the metal pump is reversed, thereby creating a suction at the end of the pipe away from the manifold and effecting the withdrawal of the molten metal from the pipe back into the furnace. As the plate 22 forming the face of the manifold is chilled by contact with the core and covering of the casting box, the metal extending into the bores in the plate is solidified and before the cylindrical core 6 is rotated it is shifted endwise a sufficient distance with respect to the manifold 21 for the projecting fingers of metal at the end of the plate to be withdrawn from the plate 22. The end of the mold opposite the manifold 21 is closed by a semicircular flanged member 25 mounted on the hub of the cylindrical core and movable axially with respect thereto and before the core is rotated the member 25 is moved away from the cast plate, as will be later described, so that the cast plate is completely released and can move with the rotating core when the latter is turned its half rotation.

As shown in Fig. 2, the core 6 is attached to the end of the sleeve 10 mounted for rotation and axial reciprocation on a fixed shaft 11. The core is grooved to provide the customary ribs on the concave face of the cast plate. Additional grooves 12 are also formed in the outer face of the core, said grooves being undercut as shown to hold the cast plate when the metal has solidified in contact with the core when the core is rotated through 180°, as above described. The sleeve 10 to which the core box is attached is rotated through 180° and then back again by means of a gear 13 keyed to the sleeve 10 and meshing with a segment 14 which is oscillated through a sufficient arc to effect a 180° oscillation of the core by means of a crank arm 15 attached to the end of the shaft 16 of an hydraulic motor 17 to which fluid under pressure is supplied from a source, not shown, through the automatic time control mechanism. The motor 17 is a vane type motor and the hydraulic fluid is delivered to first one side of the vane and then the other to effect the desired movements of the core and to hold the core in fixed position during the casting operation. As heretofore explained, this lifting of the plate is effected by a series of rollers 7 along the upper edges of the semicylindrical casting box, and as the casting box is closed these rollers lift the previously cast plate from the upper side of the cylindrical core as best shown in Fig. 4. At the end of the upward movement of the casting box the mold is fully closed and the matrix is in position with respect to the lower face of the core to receive the charge of molten metal to thereby cast a second plate.

As shown in Figs. 2 and 4, the casting box is mounted for movement at an angle to the vertical plane, that is, in a plane at right angles to the axis of the shaft of the cylindrical core. The semicylindrical casting box 8 is carried by a movable frame 26 which slides in a fixed frame portion 27. The frame 26 is also provided with a plunger 28 attached to an arm 29 depending from the frame to thereby hold the slide against tilting movement. A

counterweight mechanism 100 is connected to the plunger 28 to counterbalance the frame and casting box.

The frame 26 is elevated and lowered by means of crank arms 30 connected to the frame 27 as shown in Fig. 4. The crank arms 30 are attached at their lower ends to the cranks of a crank shaft 31 which is periodically oscillated by a hydraulic motor 32 through an arc of 180° to elevate and lower the casting box in timed relation with the rotation of the core.

The mechanism for effecting the axial reciprocation of the cylindrical core 6 and the flanged member 25 is shown in Figs. 2 and 5. As here shown the gear 13 through which the cylindrical core is rotated carries a ring 33 to which is attached a yoke lever 34 to whose lower end is connected a crank arm 35 carried by a crank shaft which is oscillated by an hydraulic motor 36 in timed relation with the operation of the hydraulic motor 32 to oscillate the yoke lever 34 once for each oscillation of the cylindrical core. Also attached to the yoke lever 34, see Fig. 5, are a pair of upstanding arms 37 connected by links 37' with the flanged member 25 at the outer end of the cylindrical core. It will be understood that the arms 37' are somewhat longer than the corresponding arms of yoke lever 34 and therefore the flanged member 25 will be shifted somewhat faster and to a somewhat greater extent than the cylindrical core itself, thus simultaneously moving the core and the cast plate away from the manifold 21 and moving the flanged member 25 away from the other end of the cast plate.

As shown in Fig. 4 the upper edges of the casting box 8 extend, when the box is closed, above the median horizontal plane of the cylindrical core and attached to the upper edges of the casting box are a pair of rails 38 on which are mounted the rollers 7 which engage the lower edges of the cast plate to lift the plate from the cylindrical core when the core box is closed. The rails 38 are movable toward and away from each other so that on the downward movement of the casting box the rollers will clear the upper edges of the freshly cast plate. After the cylindrical core is rotated through 180° the rails 38 carrying the rollers are moved toward each other to thereby bring the rollers beneath the edges of the plate which has now been inverted by the half rotation of the core. The mechanism for shifting the bars carrying the rollers toward and away from each other comprises arms 70 on which the rails 38 are mounted and which are rotatably mounted on shafts 71 carried by the box 8. Rollers 72 are mounted on the free ends of arms 71 and are adapted to engage members 39 which are in turn connected by links 73 and 74 to the frame 27. It is seen that as the box 8 is lowered, the rollers 72 will engage the members 39 to cause the arm 70 to rotate about shafts 71 and to move the rollers 7 away from each other. When the box 8 is raised the members 39 will be raised also, while at the same time they will move outward of the center line of the machine to allow rollers 7 to move toward each other. When the box reaches the limit of its upward movement and the plate has been lifted from the core 6, members 39 will fall back under the force of gravity to the positions shown in Fig. 4.

The mechanism for manipulating the cast plate during inspection comprises a frame 41 mounted for oscillation on a shaft 42 supported in fixed bearings in a position parallel with but above the axis of the shaft of the rotating core. The frame 41 is provided on each side with rollers 43 whose upper surfaces are in line with the plate supporting rollers of the casting box when it is in its elevated position and also the plate supporting rollers 44 which support the plate in its movement into the trimming section, see Fig. 1. The mechanism for oscillating the frame 41 comprises a hand crank shaft 45 having a bevel gear 46 which meshes with a bevel gear 47 attached to a stub shaft 48 geared at its upper end to bevel gears carried by the shaft 42.

The plate, if found defective, may be ejected from the frame 41 by manipulation of the hand crank 45. The

¹ It should be here observed that the contacting surfaces can be so finished as to be tight against the loss of metal under the pressure applied to the molten metal charge without being air-tight and that the air will escape from the mold as the mold is filled without building up a significant back pressure.

mechanism for effecting this ejection of the plate is shown in Fig. 6 and comprises two ejection arms 62 attached to a shaft 63 which is geared to the shaft 42 by gears 64 one of which has a lost motion connection with its shaft so that the shaft will be turned only when the hand crank 45 is turned beyond the point required for inspecting the plate.

Between the inspection station and the plate casting section is an intermediate station at which a plate may be stopped in case the inspection of a plate and its acceptance or refusal should take longer than the interval allowed by the automatic timing system. The stop mechanism at this intermediate station comprises a finger 56 carried by a tilting member 57 pivoted at 58 and periodically tilted by a plunger carried by a small hydraulic cylinder 59, as shown in Fig. 3, when it is desired to stop the plates at the intermediate station.

A similar stop mechanism having a finger 60 is provided, at the inspection station, for holding the plate against movement toward the trimming section and in the normal sequence of operations the plates will not be stopped at the intermediate station and the freshly cast plate, as soon as it is elevated above a fixed stop 61, will move of its own weight along the rollers 7 and 43 (see Fig. 2) until its forward edge engages the stop 60. As the freshly cast plate is elevated above the stop 61 the stop 60 is tilted by its plunger to release the inspection plate and is returned to stop position before the freshly cast plate reaches the stop. If, however, the inspection of a particular plate requires a longer time than allowed in the predetermined time cycle, the stop at the intermediate station may be set to stop the freshly cast plate and hold it in intermediate position until the inspection is completed and the plate released for movement into the trimming section or discharged into the furnace. To this end manually operated control buttons, not shown, are provided for effecting the operation of the stops 50 and 60.

The operation of the machine as a whole will now be described. It will be understood that the motors which effect the movement of the various parts are controlled for sequential operation by a time control system which can be set to initiate the operation of the various parts in a desired sequence and at pre-set time intervals. Such time control systems are available on the market and the details thereof form no part of the present invention. The system employed is provided with a counter which can be set to automatically repeat the cycle of operations required for casting a plate for any number of cycles. Such counters are provided with means for changing the setting during the operation of the machine controlled by the system and the change setting mechanism is connected to the defective plate throwout so as to add one cycle to the original setting for each plate throwout so that the machine, once set, will automatically cast and finish the number of plates for which it is originally set.

The control system is set to end the cycle when the casting box is in its lowermost position and the molten metal has been returned to the melting pot. In this position the operator may readily remove the matrix from the casting box and insert a fresh matrix so that the machine may be speedily restarted to automatically cast the desired number of plates from the second matrix.

The operation of the machine is initiated by a starting button and it will be understood that, as customary in machines of this kind, the circuit of the starting button is so arranged that it cannot be closed unless the water circulating pump, the vacuum pump and the heating elements for the molten metal manifold are ready for the casting operation to be initiated.

When the circuit through the starting button is completed power is supplied to the motor 32 which elevates the casting box, thereby closing the mold. The molten metal pump then functions to force the molten metal through the pipe 24 and manifold 21 into the mold cavity, the air in the mold cavity escaping through the vents above

described. After the metal is solidified the casting box is lowered, separating the matrix from the freshly cast plate, the plate being held against the core by the manifold 21 and member 25 and also by the metal of the plate extending into the undercut grooves 12. The motor 36 is then supplied with power to shift the ring 33 longitudinally to thereby move the core to the right as shown in Fig. 2, releasing the plate from the manifold. During this movement the flange member 25 is also shifted to the right by means of the arms 37 and links 37' and at a faster rate than the core to thereby release the plate at the end opposite from the manifold. The hydraulic motor 17 is then supplied with power to effect a half rotation of the core to thereby invert the plate and at the same time bring the other mold face of the core opposite the casting box so that when the casting box is again closed the mold will be ready to receive the molten metal for the second plate.

As the casting box is closed the rollers 7 engage the edges of the freshly cast plate, lifting the plate off the core. As the plate is lifted some of the metal of the ribs formed in the undercut grooves 12 breaks away. The grooves 12 are of a size and shape for the ribs formed therein to hold the plate on the core during the rotation of the core, but give way under slight force when the plate is elevated. The small amount of metal that may be broken off when the plate is lifted is melted by the heat of the metal when the next plate is cast. During the upward movement of the casting box power is supplied to the motor 36 to shift the core and the yoke lever 34 in the reverse direction to thereby restore the manifold 21 and the flange member 25 to proper position to close the ends of the mold when the core box reaches its uppermost position.

As the core box moves upwardly the end of the plate resting on the rollers 7 clears the fixed stop 61 and the plate moves by gravity to the intermediate station. As explained above, the stop 56 of the intermediate station may be set by the operator to either stop the plate or let it move on to the inspection station. The stop 60 at the inspection station is set to stop the plate and inspect it by manipulation of the hand crank 45 which can tilt the plate first in one direction and then the other so as to quickly examine its entire surface. If the plate is found defective the crank arm is moved beyond the angle for inspection purposes and when so moved the ejection arm 62 is elevated through the gearing and lost motion clutch above described, thereby lifting the plate off of the rollers 43 and discharging it into the chute leading to the melting pot. As previously explained, the movement of the crank arm through sufficient distance to eject the plate adds one cycle to the setting of the counter so that the automatic operation of the machine will continue until the desired number of plates has been cast.

In the foregoing description and accompanying drawings we have illustrated the machine as it is now being manufactured for commercial use. It will be understood, however, that the invention is not limited to the particular mechanisms herein illustrated and described, but covers all such modifications thereof as fall within the scope of the appended claims.

We claim:

1. A plate casting machine comprising a casting station, a trimming section and a cooling section arranged in axial alignment with one another and at an angle to the horizontal axis of said machine, supporting rollers arranged in alignment with one another and parallel to said axial alignment supporting and guiding plates as they move by gravity through the successive sections; said casting station comprising a rotatable and longitudinally movable cylindrical core, a semi-cylindrical casting box reciprocally movable in a direction 90° with respect to said axial alignment to and away from said core, a mold cavity formed by the adjacent opposed surfaces of said

core and said casting box having its longitudinal axis parallel to said axial alignment, molten metal delivery means extending into the lower end of said mold cavity, a semi-circular sealing member mounted on said core for axial movement therewith forming an upper wall of said mold cavity, core moving means for shifting said core axially to separate said mold cavity from said metal delivery means, and sealing member moving means for moving said sealing member axially of said core a greater distance than said core when said core is moved by said core moving means.

2. A plate casting machine according to claim 1 having in addition an inspection section positioned between said casting station and said trimming section comprising a rotatable plate support whereby said plate may be rotated for inspection.

3. A plate casting machine according to claim 1 wherein in plate lifting rollers are carried by said movable casting box in position to engage the edges of the plate on the upper side of the cylindrical core when the box is elevated to close the mold against the lower face of said core.

4. A plate casting machine according to claim 3 wherein the lifting rollers are moved outwardly on the downward movement of the box when the plate has solidified.

5. A plate casting mechanism comprising an inclined cylindrical core having two mold forming surfaces of substantially semi-cylindrical extent, core rotation means for periodically rotating said core 180° about its longitudinal axis, an inclined semi-cylindrical casting box co-operating with one of said mold forming surfaces to form a mold cavity, box moving means for moving said box toward and from said core in the interval between its successive half rotations, a semi-circular metal delivery manifold having a plurality of metal delivery nozzles therein provided at the lower end of said core and box when said core and box are in the casting position to form a lower wall of said mold, a semi-circular sealing member mounted on said core for axial movement therewith forming an upper mold wall, core moving

means for shifting said core axially to separate said mold and the formed casting from said manifold and to remove cast metal from said nozzles, and sealing member moving means for moving said sealing member axially of said core a greater distance than said core when said core is moved by said core moving means.

6. In a plate casting machine a casting box, a core, said casting box and core forming a mold cavity, core moving means for moving said core axially along its longitudinal axis, box moving means for moving said box away from and towards said core, an upper seal forming an upper wall of said cavity, seal moving means for moving said seal parallel to said core a greater distance than when said core is moved by said core moving means, a molten metal delivery manifold forming a bottom wall of said mold cavity, a plurality of nozzles in said manifold opening into said cavity, a source of molten metal, a passage from said source to said manifold, and a reversible pump means for forcing said molten metal through said passage into said manifold and mold cavity; said pump means when reversed creating a suction to withdraw molten metal from said manifold.

7. A plate casting machine according to claim 5 wherein in the molten metal is withdrawn from the metal delivery means when the plate has solidified.
